Attorneys.

UNITED STATES PATENT OFFICE.

GAY WOLLENWEBER, OF SAVANNAH, GEORGIA.

LIQUID DISPENSER.

Application filed August 10, 1922. Serial No. 580,984.

To all whom it may concern:

Be it known that I, GAY WOLLENWEBER, a citizen of the United States, residing at Savannah, in the county of Chatham and

5 State of Georgia, have invented a new and useful Liquid Dispenser, of which the following is a specification.

This invention relates to liquid dispensing devices, and more particularly to devices 10 especially designed for dispensing disinfectants in liquid form.

The primary object of the invention is to provide a device of this character which will operate by capillary flow, novel means 15 being provided for regulating the flow of liquid from the container in which the liquid is positioned.

Another object of the invention is to provide a device of this character which will 20 protect the liquid contained therein, and reduce the evaporation of the liquid, to a minimum.

With the foregoing and other objects in view which will appear as the description 25 proceeds, the invention resides in the combination and arrangement of parts and in the details of construction hereinafter described and claimed, it being understood that changes in the precise embodiment of 30 the invention herein disclosed, may be made within the scope of what is claimed, without departing from the spirit of the invention.

Referring to the drawings:

35 The figure illustrates a sectional view through the dispenser.

Referring to the drawings in detail, the reference character 5 designates the container proper in which is positioned the inner receptacle 6, that carries the cover 7 at one end thereof, which cover is designed to be positioned over the open end of the container 5 to close the same.

The receptacle 6 is of a diameter less than 40 the diameter of the container 5 to provide a fluid chamber between the container and receptacle, it being understood that the re-

ceptacle has its lower end slightly spaced from the bottom of the container 5 to permit fluid to pass from the receptacle to the 50 fluid chamber.

A notched bar is indicated at 8 and is also positioned in the fluid chamber, the lower end of the notched bar being tubular in formation as indicated at 9 to accommodate 55 the wick 10, which has its opposite end positioned in the fluid chamber to absorb fluid therein. The wick 10 is shown as resting on one of the shoulders 11 formed by the notched portions of the bar 8, whereby the 60 length of the wick may be increased or decreased to vary the flow of liquid from the fluid chamber.

In use, the receptacle 6 is filled with the fluid to be dispensed, and the container is 65 positioned thereover. The device is now inverted or moved to a position as indicated by the figure of the drawings, whereupon the fluid by capillary attraction passes through the wick and is deposited thru the 70 tubular member 9 in drops.

Having thus described the invention, what is claimed as new is:—

In a fluid dispensing device, a container having an opening, a vertically disposed bar 75 having a discharge tube formed at one end thereof supported within the container, said discharge tube being positioned in the opening, said bar having shoulders arranged in spaced relation with each other, a wick having one end thereof positioned in the container and having its intermediate portion adapted to be positioned on the shoulders to adjust the length of the wick, and the opposite end of said wick being positioned in 80 the discharge tube.

In testimony that I claim the foregoing as my own, I have hereto affixed my signature in the presence of two witnesses.

GAY WOLLENWEBER.

Witnesses:

W. H. REDDICK,
J. B. BLACKWELL.
